OILING DEVICE

Filed Oct. 18, 1928

INVENTOR
CARLTON D. STEWART
BY *W. M. Brady*
ATTORNEY

UNITED STATES PATENT OFFICE

CARLTON D. STEWART, OF BERKELEY, CALIFORNIA, ASSIGNOR TO THE WESTINGHOUSE AIR BRAKE COMPANY, OF WILMERDING, PENNSYLVANIA, A CORPORATION OF PENNSYLVANIA

OILING DEVICE

Application filed October 18, 1928. Serial No. 313,296.

This invention relates to a lubricating device, and more particularly to an automatic lubricator for fluid compressors of the type disclosed in Patent No. 1,337,687 of C. L. 5 Bubb, dated April 20, 1920, and reissued as Reissue Patent No. 15,267, dated January 17, 1922.

The principal object of my invention is to provide an improved lubricator of the above 10 type, in which the parts may be easily disassembled for cleaning and having means whereby different lubricant feeding rates may be obtained, as desired.

In the accompanying drawing, the single 15 figure is a central sectional view of a lubricator embodying my invention.

The lubricator may comprise a body 1 having a lubricant receiving chamber or receptacle 2. A discharge passage 3 extends 20 through the neck portion 4 of the body and is connected to a pipe 5 which leads to the air cylinder of the fluid compressor.

Secured centrally within the body is a hollow stud or tube 6, having an annular flange 25 7 which engages a bearing surface of the body. The upper end of the lubricator is closed by a threaded filling cap 8, the body being interiorly threaded to receive the cap.

Mounted on the stud 6 is a sleeve 9 having 30 a neat sliding fit on said stud, except that at each end the bore of the sleeve is slightly enlarged, as shown at 10 and 11, so as to provide a restricted feed passage from the chamber 2, through which oil is supplied by capillary attraction to a radial passage 12 in the stud 6 which opens to the central bore 13. The bore 10 is of different diameter than the bore 11, so as to provide different oil feed rates.

35 The sleeve 9 is also provided with one or more notches 14 at each end, to ensure flow of oil from the chamber 2 to the bore 10 or 11, as the case may be.

Interposed between the top of the sleeve 40 9 and the cap 8 is a thimble 15, preferably pressed out of sheet metal, and cut in the upper end of the thimble is a spring clip 16.

The side wall of the thimble is provided with an opening 17.

45 In operation, liquid lubricant from cham-

ber 2 flows through the notches 14 and rises in the bore 10 by capillary attraction, so that the lubricant enters the passage 12 and flows into the bore 13, whence the lubricant flows by gravity through the passage 3 and pipe 5 to the fluid compressor cylinder to which the lubricator is connected.

When it is necessary to again fill the chamber 2 with lubricant, the cap 8 is removed and the lubricant is poured in around the sleeve 9. The thimble 15 remaining in place, prevents the lubricant from entering the bore 13 of the stud 6.

The thimble 15 serves to hold the sleeve 9 in place against vertical movement and the spring clip 16 ensures lost motion, due to any inaccuracies in the fitting of the cap 8. The opening 17 permits free flow of fluid back and forth, so that changes in fluid pressure in the bore 13 due to the reciprocation of the compressor piston will be equalized in the chamber 2.

The sleeve 9 may be easily removed for cleaning, in case dirt or carbonized oil should clog the feed passages, and this is facilitated by providing the feed spaces 10 and 11 in the sleeve, rather than in the stud 6.

One of the feed bores, such as the bore 10, may be for a slow feed, while the other bore 11 may be slightly larger to provide a more rapid oil feed, and if the more rapid feed is desired, it is only necessary to remove the sleeve 9 and apply the same in a reversed direction to the stud 6, so that the feed bore 11 is at the lower or feed position on the stud, instead of the bore 10.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. A lubricator comprising a body having a chamber containing a lubricant, a member having a lubricant discharge passage, a second member removably mounted on the first member and adapted in one position to provide a restricted passage for the supply of 95 100

lubricant from said chamber to said discharge passage and adapted when applied to the first member in the reversed position to provide a restricted passage of greater flow capacity than the first restricted passage for the supply of lubricant.

2. A lubricator comprising a casing having a lubricant containing chamber, a tubular member mounted in said casing and having

10 a lubricant discharge passage, a reversible sleeve mounted on said member and spaced from said member at its opposite ends, to provide passages of different flow capacities, lubricant being supplied from said chamber

15 to said discharge passage through one passage in one position of said sleeve and through the other passage when the position of said sleeve is reversed.

3. A lubricator comprising a casing having

20 a lubricant containing chamber, a tubular member mounted in said casing, a sleeve slidably mounted on said member, the bore of the sleeve at its opposite ends being enlarged, so that in one position, one of said enlarged

25 bores provides communication for the supply of lubricant from said chambers, and when the position of said sleeve is reversed, the other enlarged bore provides communication for the supply of lubricant, the enlarged

30 bores being of different flow areas.

4. A lubricator comprising a casing having a lubricant containing chamber, a tubular member mounted in said casing and having a lubricant discharge passage, a sleeve mounted on said member, a filling cap removably applied to said casing, a member interposed between said cap and said sleeve and having yielding means through which said cap presses said member against said sleeve.

35 5. A lubricator comprising a casing having a lubricant containing chamber, a tubular member mounted in said casing and having a lubricant discharge passage, a sleeve mounted in said member, a filling cap re-

45 movably applied to said casing, and a removable cap mounted on top of said sleeve, to prevent lubricant from entering said tubular member when said chamber is being filled with lubricant.

50 In testimony whereof I have hereunto set my hand, this 8th day of October, 1928.

CARLTON D. STEWART.
